UNITED STATES PATENT OFFICE.

WILLIAM M. TAYLOR, OF WESTON, WEST VIRGINIA.

IRONING-BOARD AND TABLE COMBINATION.

1,175,194.

Specification of Letters Patent. Patented Mar. 14, 1916.

Application filed September 13, 1915. Serial No. 50,529.

To all whom it may concern:

Be it known that I, WILLIAM M. TAYLOR, a citizen of the United States, residing at Weston, in the county of Lewis and State of West Virginia, have invented new and useful Improvements in Ironing-Board and Table Combinations, of which the following is a specification.

My invention relates to new and useful improvements in combined tables and ironing boards, and my object is to provide a table and movably mount a top thereon.

A further object is to hingedly attach an ironing-board to parts of the table in such manner that it may be moved to a position below the top or extended above the top for use. And a further object is to provide means for securing the ironing board in its elevated position.

Other objects and advantages will be hereinafter set forth and more particularly pointed out in the accompanying specification.

In the accompanying drawings which are made a part of this application, Figure 1 is an end elevation of the table showing the ironing board in folded position. Fig. 2 is a detail transverse vertical sectional view through a portion of the table and the ironing board showing the board in elevated position, and Fig. 3 is a side elevation of a portion of the table and ironing board in operative position.

Referring to the drawings in which similar reference numerals designate corresponding parts throughout the several views, 1 indicates a table which may be constructed in any preferred manner, preferably comprising frame bars 2 arranged substantially rectangular, which frame is attached to the upper ends of supporting legs 3. Mounted upon the frame bars 2 is a top 4 which is provided at its ends with angle-shaped strips 5 which engage tongues 6 upon the end frame bars and slide thereon, said strips 5 permitting lateral movement of the table top for a purpose to be hereinafter set forth.

Secured to the supporting legs 3 at a point between their upper and lower ends is a shelf or platform 7, and extending from said platform to one of the side frame bars is a post 8 and between said post and one of the supporting legs is positioned my improved form of ironing board 9, said board having standards 10 attached thereto through which and the post 8 and support-

ing leg 3 is introduced a pivot bolt 11 so that the board 9 may be lowered until it rests upon the shelf 7 or elevated to extend above the top 4.

One edge of each standard 10 is provided with a notch 12 which registers with one of the side frame bars when the board is in elevated position, and in order to securely hold the board in elevated position, a latch 13 is pivoted to the faces of the standards having the notches therein and said latches are bowed in their length so that they will direct pressure against the outer face of the frame bar and securely hold the board in elevated position, each latch having a handle 14 for operating the same.

The ironing board, when not in use, is swung on its pivot until one edge thereof rests upon the shelf 7 when the table may be used for any desired purpose, but when the ironing board is to be used, the top 4 is moved laterally and the board swung upwardly until the standards assume a vertical position when the handles 14 are rotated to dispose the latches over the outer face of the frame bar 2 to hold the standards in vertical position, the top 4 being then moved inwardly until the edge thereof engages the inner edges of the standards, thereby assisting in holding the standards in vertical position.

It will thus be seen that I have provided a very simple form of combined table and ironing board and have so arranged the ironing board that when not in use, it can be conveniently housed below the table top so as not to interfere with the use of the table. And it will likewise be seen that the ironing board can be very easily and quickly secured in position for use when desired, and by attaching a cross bar 15 at the pivoted ends of the standards, they will be fully braced and held in spaced relation. It will likewise be understood that instead of slidably mounting the table top so that it may be moved out of the path of the ironing board when the same is being raised or lowered, any suitable structure may be provided for disposing the top out of the path of the ironing board.

Having thus fully described my invention what I claim as new and desire to secure by Letters Patent of the United States, is:

1. A combined table and ironing board comprising the combination with a table structure having a movable top, of an iron-

ing board, standards engaged to said ironing board, means to pivotally attach one end of the standards to parts of the table structure, and a latch on each standard adapted 5 to be moved into engagement with parts of the table structure to hold the standards in vertical position.

2. The combination with a table structure comprising supporting legs, frame bars at 10 the upper ends of the supporting legs, a movable top for the table structure and a post attached to parts of the table structure adjacent one of the supporting legs, of an ironing board, standards attached to said 15 ironing board, a pivot belt connecting the

opposite ends of the standards between said post and one of the table legs, said standards having notches in one edge thereof to register with one of the frame bars, latches pivoted to said standards and having bowed 20 portions, and handles attached to said latches whereby they may be moved into or out of engagement with the frame bar engaged by the standards.

In testimony whereof, I affix my signature 25 in the presence of two witnesses.

WILLIAM M. TAYLOR.
